(57) **CLAIM**

The ornamental design for a catheter hub device, as shown
and described.

DESCRIPTION

FIG. 1 is a perspective front, top and side view of a catheter
hub device.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines show portions of the design that form no
part of the claimed design.
